UNITED STATES PATENT OFFICE

138,330

DESIGN FOR A WALKING CANE

George Byron Wisecarver, Pikeville, Ky.

Application April 10, 1944, Serial No. 113,206

Term of patent 14 years

(CL. D88—4)

To all whom it may concern:

Be it known that I, George B. Wisecarver, a citizen of the United States of America, residing at Pikeville, county of Pike, and State of Kentucky, have invented a new, original, and ornamental Design for a Walking Cane, of which the following is a specification, reference being had to the accompanying drawing, forming a part thereof, wherein the figure is a perspective view of a walking cane, showing my new design.

I claim:

The ornamental design for a walking cane, as shown.

GEORGE BYRON WISECARVER.
